INVENTOR,

Aloysius I. Raef.

BY HIS ATTORNEYS,

Higdon & Higdon.

UNITED STATES PATENT OFFICE.

ALOYSIUS I. RAEF, OF KANSAS CITY, MISSOURI.

CREEPER ATTACHMENT FOR HORSESHOES.

SPECIFICATION forming part of Letters Patent No. 650,868, dated June 5, 1900.

Application filed February 23, 1900, Serial No. 6,212. (No model.)

To all whom it may concern:

Be it known that I, ALOYSIUS I. RAEF, a citizen of the United States, and a resident of Kansas City, in the county of Jackson and 5 State of Missouri, have invented certain new and useful Improvements in Creeper Attachments for Horseshoes, of which the following is a specification.

My invention relates to improvements in 10 creeper attachments for horse or mule shoes and aims to provide a device for attachment to such shoes for the purpose of securing a sure footing for the animal when traveling upon slippery or otherwise-difficult roads; 15 and said invention relates especially to a creeper attachment capable of being applied to the under surface of the shoe, the same consisting of a skeleton frame having the same general contour as that of the shoe, carrying upon its lower surface toe and heel 20 calks, upon its outer, lateral, and front edges outwardly-extending lugs capable of being bent over against the corresponding outer edges of the shoe, and upon its inner edges 25 inwardly-extending lugs adapted to be bent over the inner edges of the shoe, so as to hold the device securely in place on the shoe.

In the accompanying drawings, Figure 1 is 30 a side elevation of the creeper attachment embodying my invention detached. Fig. 2 is an elevation of the bottom of a shoe with 35 the creeper in place, but not yet fully secured to the shoe. Fig. 3 is an elevation of the upper side of the shoe with creeper fully attached, showing the terminals of the lugs and flanges which hold the creeper in place on the shoe. Fig. 4 is a perspective view of the 40 under side of the shoe with the creeper attached and fully secured thereon. Fig. 5 is a rear end view of the shoe and creeper before being secured together. Fig. 6 is a cross-section, through one side of the shoe and 45 creeper after the same are secured together, on the line VI VI of Fig. 3.

For clearness it may be stated that in the 50 description thus far and in that to follow, also in the claims, words indicating direction—such as "upper," "under," "top," "bottom," &c.—have been and will be used with reference to the shoe and creeper in the position they would normally occupy on the hoof.

The shoe proper, 1, for use with my device

is preferably of the ordinary form, without calks, but provided at the rear end, upon each side, with a downwardly-projecting right-angled shoulder 2. It is also provided on its upper surface with the usual downward level 3, extending around its inner edge.

The creeper is made, preferably, of steel and normally consists of a skeleton frame 4, made 60 as light as is compatible with the requisite strength. It carries at its front end a downwardly-projecting integral toe-calk 5 and at its rear ends integral heel-calks 6, all having sharp edges. Between the toe-calk and heel-calks extends upon each side an integral downwardly-projecting V-shaped rib 7 for greater strength. An integral lug 8 projects forward from the outer edge of the toe portion, and lateral lugs 9 extend outwardly from 70 the rear ends. Upon the inner edges of the creeper an integral flange 10 projects rearwardly from the front or toe portion, and integral side flanges 11 project inwardly toward each other, said side flanges beginning at 75 about the middle of the creeper and extending rearward nearly to the calks 6. Before the creeper is applied to the shoe said flanges 10 11 are bent over, upward, and outward, so that when on the shoe they will engage the 80 inner edges of the shoe, as shown most clearly in Fig. 3.

The creeper as first formed or in its normal state has its rear ends drawn toward each other, as shown in dotted lines in Fig. 2. It 85 is applied to the shoe cold and may be applied either before or after the shoe is on the hoof. It is applied to the bottom of the shoe, as in Fig. 2, the bent-up flange 10 being first made to engage the beveled inner edge of the 90 toe portion of the shoe. The rear ends of the creeper are then forced outward by the use of any suitable tool until the flanges 11 are brought to bear firmly against the inner edges of the shoe, as in Fig. 3. The rear ends of the 95 creeper are also made to abut against the inner faces of the shoulders 2 on the rear ends of the shoe. The lug 8 is then hammered over against the front edge of the toe and the lugs 9 bent up against the outer rear edges. 100 It will be seen that the creeper when thus applied is secured against displacement or movement in any direction, either inward or outward, forward or backward, and cannot pos-

sibly become accidentally detached from the hoof.

The bevel 3 on the upper inner edge of the shoe provides a space between the shoe and hoof for the bent-over edges or lips of the flanges 10 11, so that the same cannot come in contact with the hoof.

I provide a slight modification of the creeper described for application to old shoes already furnished with a toe-calk, which consists in omitting the toe-calk from its usual location on the creeper, but providing two calks of smaller size, one upon each side, near the toe, so that the toe-calk on the shoe will lie between them. The frame 4 and rib 7 will extend around the front of the creeper, abutting against the inner side of the toe-calk on the shoe.

Having described my invention, I claim as new and desire to secure by Letters Patent—

1. A creeper attachment for horse or mule shoes, adapted to be applied to the under surface of the shoe, the same consisting of a skeleton frame provided with toe and heel calks, a forwardly-projecting lug adapted to bear against the outer edge of the toe of the shoe, lateral lugs projecting outwardly from the rear ends of said frame, adapted to bear against the outer edges of the rear ends of

the shoe, and front and side flanges projecting inwardly from the inner edges of said frame adapted to be bent over and bear against the inner edges and upper surface of the shoe, substantially as set forth.

2. The combination with a horse or mule shoe, provided with angular shoulders at its rear ends, and a downward bevel on the inner margin of its upper surface, of a creeper attachment consisting of a skeleton frame provided with toe and heel calks, said heel-calks bearing against said shoulders, a forwardly and upwardly projecting lug, bearing against the outer edge of the toe of the shoe, lateral lugs projecting outward and upward from the rear ends of said frame, and bearing against the outer edges of the rear ends of the shoe, and front and side flanges projecting inward and upward from the inner edges of said frame, and bearing against the inner edges and the beveled upper surface of said shoe, substantially as set forth.

In testimony whereof I affix my signature in the presence of two witnesses.

ALOYSIUS I. RAEF.
